UNITED STATES PATENT OFFICE

WALTER J. ARMSTRONG, OF COLUMBUS, OHIO, ASSIGNOR TO THE JEFFREY MANUFACTURING COMPANY, OF COLUMBUS, OHIO, A CORPORATION OF OHIO

PULVERIZING MACHINE

Application filed April 28, 1927, Serial No. 187,400. Renewed October 3, 1929.

The present invention relates to certain new and useful improvements in pulverizing machines of the class wherein a rotor is adapted to rapidly revolve within a casing to engage and pulverize material therein.

In the use of machines of the class referred to, difficulty has arisen from the accidental inclusion with the material to be pulverized of unbreakable fragments such as metallic tools, bolts, nuts, etc. Safety devices have heretofore been provided wherein, by the excessive strains occasioned by contact of the rotor with such unbreakable objects, the actuating power devices are automatically disconnected from the rotor thereby preventing further injury to the machine. These devices have been unsatisfactory because of the shocks and strain arising from the inertia of the rotor and the time required for the action of the safety devices.

It is the especial object of this invention to provide, in a machine of the class described, means to absorb the shocks produced by engagement of the rotor with unbreakable objects within the casing, thereby affording time for the satisfactory operation of the safety devices above referred to.

A further object is to provide auxiliary safety devices adapted to cooperate with the shock absorbing devices to relieve the accidental strains above described.

These and other objects will appear in the following specification reference being had to the accompanying drawings of which

Fig. 1 is a side elevation of a machine built in accordance with my present invention.

Fig. 2 is an elevation of the end of the machine illustrated in Fig. 1 remote from the power connection whereby the machine is actuated.

Fig. 3 is an elevation of the power end of the machine illustrated in Figs. 1 and 2.

Fig. 4 is a transverse sectional view taken along the line IV—IV of Fig. 1.

Fig. 5 is a fragmentary detail on an enlarged scale of certain parts shown in Fig. 4.

Like numerals refer to similar parts in the several figures.

The preferred embodiment of my invention comprises a base frame 1 of generally

rectangular form upon which are mounted the operative parts of the machine. At each end of the frame there are formed brackets 2 to which are attached the journal bearings 3. Mounted in the journal bearings 3 is a longitudinally extending shaft 4 upon which the rotor is mounted. The rotor is of the well known type comprising a plurality of concentric discs 5 arranged in spaced relation longitudinally of the shaft 4, and between these discs are mounted the pulverizing elements. The pulverizing elements are preferably of trifoliate form, having diverging arms 6, 7 and 8, each of which is perforated to receive the supporting rods 9. The rods 9 extend longitudinally of the rotor through suitable apertures of the discs 5, and the proportion of the parts are such that two of the arms 7 and 8 engage the rods 9 to hold the third arm 6 rigidly in radial projection beyond the periphery of the discs 5.

Fixed to the projecting end 10 of the shaft 4 is a hub 11 upon the periphery of which is rotatively mounted a pulley wheel 12 adapted to engage an endless belt, not shown in the drawing, by which power is transmitted to cause the revolution of the rotor. The pulley 12 is connected with the hub 11 by one or more shear pins 13 which extend through suitably placed apertures in the web 14 of the pulley 12 and in a circumferentially extending flange 15 of the hub 11. The shear pins 13 are formed of suitable frangible material and their proportions are such that a strain in excess of a definitely predetermined maximum will cause them to shear and thereby disconnect the pulley from the rotor to prevent injur of the machine arising from overloads such as would be occasioned by the engagement of unpulverizable objects accidentally included in the material which is to be pulverized.

Attached to the upper edges of the base frame 1 are the end walls 16 of the pulverizing chamber, and at their upper forward corners these end walls are connected together by a through bolt 17. Suspended from the bolt 17 is a breaker plate 18 which extends between the end walls 16 and constitutes the forward wall of the pulverizing

chamber. A curved plate 19 attached to the end walls 16 closes the rearward side of the pulverizing chamber, and a cover plate 20 may be provided to partially close the top of the pulverizing chamber when the conditions of operation render such closing desirable. Material to be pulverized is introduced through the opening 21 at the top of the pulverizing chamber, and falls directly upon the 10 rotor to be thrown by centrifugal force against the breaker plate 18. The fractured fragments resulting from such contact are reflected rearwardly and fall again upon the rotor for further action thereby. At its lower

15 end the breaker plate 18 is shaped to closely approach the path of the pulverizing hammers 6 with which it cooperates to prevent the escape of unpulverized material from the pulverizing chamber.

20 Beneath the rotor there may be provided a semi-cylindrical floor composed of longitudinally extending grate bars 22, supported upon suitable flanges 23 of the base frame 1. The bars 22 are held in spaced relation to each other by the spacer blocks 24, and at each end of the series is a clamping bar 25 and 26. The bars 25 and 26 are mounted in suitable apertures of the base frame 1, and the bar 26 is engaged by the clamping screws 30 (see Fig. 2) by which the bars and spacer blocks are clamped in place. The clamping bar 25 is preferably chamfered on its upper inner edge, to prevent the lodgment thereon of material passing from the pulverizing 35 chamber when the breaker plate 18 has been swung outwardly under the impact of the hammers 6 transmitted through unpulverizable objects accidentally mingled with the material that is to be pulverized. Under 40 some conditions of service the grate bars 22 may be omitted from the machine without departure from the spirit of my invention.

Pivoted mounted upon the through bolt 17 are the downwardly depending arms 28 45 which are shaped to occupy a position parallel with and in the rear of the breaker plate 18. These arms 28 extend beyond the lower end of the breaker plate 18, and they are attached to the frame 1 by the eye bolts 29. 50 Each of the eye bolts 29 engages a shear pin 30 which is supported in suitable apertures formed in the lugs 31 attached to the base frame 1. These shear pins 30 are composed of frangible material of suitable character, 55 and their dimensions are so proportioned that a predetermined outward pressure upon the arms 28 will cause their rupture, thereby releasing the arm 28 to swing rearwardly upon its pivotal support. Positioned between each 60 of the pivoted arms 28 and the breaker plate 18 are compression springs 32 adapted to resiliently hold the breaker plate 18 in operative position. Means for adjusting the initial compression of the springs 32 is provided in the bolts 33 which extend through

the breaker plate 18 and the arm 28 concentric with the springs 32. Means for adjustment of the position of the arms 28 and therewith the breaker plate relative to the rotor is provided in the nuts 34 and 35 which are screw threaded to the eye bolts 29, at each side of arms 28. By the adjustment of the nuts 34 and 35 the width of the throat between the breaker plate 18 and the rotor may be varied to adapt the machine to the grinding of finer or coarser products. 75

In the operation of machines of the class described, unpulverizable objects accidentally included with the material to be pulverized tends to produce shocks which, if not relieved, may wreck the machine. It has long been the practice to provide shearing pins as for example the pins 13, adapted by their rupture to disconnect the actuating power from the rotor. The fineness of the product derived from such a machine is a factor of the speed of the rotor. In machines intended for very fine grinding the pulverizing hammers are commonly pivotally attached to the rotor, and are held in radial projection by the centrifugal force generated by their velocity. Such mounting of the hammers provides a resilience of action which sufficiently protects the machine. When, however, a relatively coarse product is desired, the speed of the 85 rotor must be so reduced that the centrifugal force developed is insufficient to maintain the pulverizing hammers in operative position. This has caused the development of rotors having the hammers rigidly attached. 90 When these rigid hammers engage an unpulverizable object, because of the inertia of the rotor and the time required for the rupture of the shearing pins 13, a shock is transmitted to the frame, often wrecking the machine. 100 By my present invention the resilient support of the breaker plate 18 absorbs such shocks and affords sufficient time for the shearing of the pin 13, while the auxiliary shearing pin 30 affords additional relief rendering more certain the protection of the machines. 105

As has been stated, springs 32 have been provided intermediate the breaker plate and shear pins 30 in view of their instantaneous response when unbreakable fragments are encountered. In actual practice, the springs may be so tensioned as to be able to yield slightly, without injury to the shear pins, to permit the passage of small particles of foreign substance. Upon a further compression of the springs than this, however, the increased counterforce of the springs will cause the shearing of the pins. The tension of the springs is always such that the breaker plate 115 will not yield under the impact of pulverizable material, since otherwise the uniformity 120 of the product would be affected.

It is to be understood that I do not limit myself to the precise construction here illus- 130

trated as the machine may be subject to wide variation as to details without departure from the spirit of my invention.

What I claim is:

5. 1. In a pulverizing machine, the combination with a casing enclosing a pulverizing chamber, of a rotor rotatable within the chamber, a breaker plate pivotally mounted adjacent the rotor adapted to cooperate therewith to pulverize material fed thereto, an abutment positioned behind said breaker plate, a spring interposed between said abutment and said breaker plate, said abutment being attached to said casing by means releasable by predetermined pressure upon the breaker plate as and for the purpose set forth. 70
10. 2. In a pulverizing machine, the combination with a casing enclosing a pulverizing chamber, of a rotor rotatable within the chamber, a breaker plate positioned at the forward side of said chamber pivotally supported at one end and adapted to cooperate with said rotor to pulverize material fed thereto, an arm positioned behind said breaker plate pivotally attached to said casing at its end adjacent the pivot point of said plate and resiliently connected to the breaker plate, and means to secure the other end of the arm to the casing as and for the purpose set forth. 75
15. 3. In a pulverizing machine, the combination with a casing enclosing a pulverizing chamber, of a rotor rotatable within the chamber, a breaker plate positioned at the forward side of the chamber pivotally supported at one end and adapted to cooperate with the rotor to pulverize material fed thereto, an arm positioned behind said breaker plate pivotally attached to said casing at its end adjacent the pivot point of said plate and resiliently connected to the breaker plate, and means to secure the other end of the arm to the casing as and for the purpose set forth. 80
20. 4. In a pulverizing machine, the combination with a casing enclosing a pulverizing chamber, of a rotor rotatable within the chamber, a breaker plate positioned at the forward side of said chamber pivotally supported at one end and adapted to cooperate with said rotor to pulverize material fed thereto, an arm positioned behind said breaker plate pivotally attached to said casing at its end adjacent the pivot point of said plate and resiliently connected to the breaker plate, and means releasable by a predetermined pressure upon the breaker plate to secure the other end of said arm to the casing as and for the purpose set forth. 85
25. 5. In a pulverizing machine, the combination with a casing enclosing a pulverizing chamber, of a rotor rotatable within the chamber, a breaker plate positioned at the forward side of said chamber pivotally supported at its upper end and adapted to cooperate with said rotor to pulverize material fed thereto, an arm positioned behind said breaker plate pivotally attached to said casing at its end adjacent the pivot point of said plate and resiliently connected to the breaker plate, and means releasable by a predetermined pressure upon the breaker plate to secure the lower end of said arm to the casing as and for the purpose set forth. 90
30. 6. In a pulverizing machine, the combination with a casing enclosing a pulverizing chamber, of a rotor rotatable within the chamber, a breaker plate positioned at the forward side of the chamber pivotally supported at one end and adapted to cooperate with the rotor to pulverize material fed thereto, an arm positioned behind said breaker plate pivotally attached to said casing at its end adjacent the pivot point of said plate and resiliently connected to the breaker plate, and means including a frangible element adapted to attach said arm to the casing, power devices adapted to actuate said rotor, and means including a frangible element adapted to connect said power devices with said rotor as and for the purpose set forth. 95
35. 7. In a pulverizing machine, the combination with a casing enclosing the pulverizing chamber, of a rotor rotatable within the chamber, a breaker plate positioned at the forward side of said chamber pivotally supported at its upper end and adapted to cooperate with said rotor to pulverize material fed thereto, an arm positioned behind said breaker plate pivotally attached to said casing at its end adjacent the pivot point of said plate and resiliently connected to the breaker plate, and means releasable by a predetermined pressure upon the breaker plate to secure the lower end of said arm to the casing as and for the purpose set forth. 100
40. 8. In a pulverizing machine, the combination with a casing enclosing the pulverizing chamber, of a rotor rotatable within the chamber, a breaker plate positioned at the forward side of the chamber pivotally supported at one end and adapted to cooperate with the rotor to pulverize material fed thereto, an arm positioned behind said breaker plate pivotally attached to said casing at its end adjacent the pivot point of said plate and resiliently connected to the breaker plate, and means releasable by a predetermined pressure upon the breaker plate to adjustably secure the other end of said arm to the casing as and for the purpose set forth. 105
45. 9. In a pulverizing machine, the combination with a casing enclosing the pulverizing chamber, of a rotor rotatable within the chamber, a breaker plate positioned at the forward side of the chamber pivotally supported at its upper end and adapted to cooperate with said rotor to pulverize material fed thereto, an arm positioned behind the breaker plate pivotally attached to said casing at its upper end, means releasable by a predetermined pressure upon the breaker plate to attach the lower end of said arm to the casing, a spring interposed between said 110
50. 10. In a pulverizing machine, the combination with a casing enclosing the pulverizing chamber, of a rotor rotatable within the chamber, a breaker plate positioned at the forward side of the chamber pivotally supported at one end and adapted to cooperate with the rotor to pulverize material fed thereto, an arm positioned behind the breaker plate pivotally attached to said casing at its upper end, means releasable by a predetermined pressure upon the breaker plate to attach the lower end of said arm to the casing, a spring interposed between said 115
55. 11. In a pulverizing machine, the combination with a casing enclosing the pulverizing chamber, of a rotor rotatable within the chamber, a breaker plate positioned at the forward side of the chamber pivotally supported at its upper end and adapted to cooperate with said rotor to pulverize material fed thereto, an arm positioned behind the breaker plate pivotally attached to said casing at its upper end, means releasable by a predetermined pressure upon the breaker plate to attach the lower end of said arm to the casing, a spring interposed between said 120
60. 12. In a pulverizing machine, the combination with a casing enclosing the pulverizing chamber, of a rotor rotatable within the chamber, a breaker plate positioned at the forward side of the chamber pivotally supported at one end and adapted to cooperate with the rotor to pulverize material fed thereto, an arm positioned behind the breaker plate pivotally attached to said casing at its upper end, means releasable by a predetermined pressure upon the breaker plate to attach the lower end of said arm to the casing, a spring interposed between said 125
65. 13. In a pulverizing machine, the combination with a casing enclosing the pulverizing chamber, of a rotor rotatable within the chamber, a breaker plate positioned at the forward side of the chamber pivotally supported at its upper end and adapted to cooperate with said rotor to pulverize material fed thereto, an arm positioned behind the breaker plate pivotally attached to said casing at its upper end, means releasable by a predetermined pressure upon the breaker plate to attach the lower end of said arm to the casing, a spring interposed between said 130

arm and said breaker plate, and means to adjust the initial compression of said spring as and for the purpose set forth.

10. In a device of the class described, a 5 rotor, a breaker plate for cooperation therewith, means to maintain said breaker plate in constant operative relation to said rotor under normal working conditions, said means being adapted to yield to permit the passage of small unbreakable particles between the rotor and plate, and means entirely releasable to permit the movement of the plate to inoperative position relative to the rotor upon the entrance between the two elements 10 of larger unbreakable fragments.

11. In a pulverizing machine, a rotor, a breaker plate for cooperation with said rotor, an abutment behind said breaker plate, cushioning means between said abutment and said 20 plate, means for altering the distance between said abutment and plate to regulate said cushioning means, and means for moving said abutment to adjust said plate relative to said rotor.

25. 12. In a pulverizing machine, a rotor, a breaker plate for cooperation with said rotor, an abutment behind said breaker plate, cushioning means between said abutment and said 30 plate, means for altering the distance between said abutment and plate to regulate said cushioning means, means for moving said abutment to adjust said plate relative to said rotor, and means yieldable at a predetermined pressure for securing said abutment 35 in determined position relative to said rotor.

13. In a pulverizing machine, a rotor, a breaker plate pivotally supported in operative relation to said rotor, an abutment member extending across and behind said breaker 40 plate, said abutment member being pivotally mounted at one end, cushioning means between said abutment member and said plate, adjustable means connecting said abutment 45 member and said plate for altering the distance between them and thereby regulating said cushioning means, and adjustable means for securing the other end of said abutment member with said plate in adjusted position 50 relative to said rotor.

14. In a pulverizing machine, a rotor, a breaker plate pivotally supported in operative relation to said rotor, an abutment member extending across and behind said breaker 55 plate, said abutment member being pivotally mounted at one end, cushioning means between said abutment member and said plate, adjustable means connecting said abutment 60 member and said plate for altering the distance between them and thereby regulating said cushioning means, and adjustable means for securing the other end of said abutment member with said plate in adjusted position 65 relative to said rotor, the mounting means

for said abutment member including means frangible at a predetermined pressure.

15. In a machine of the class described, a 70 rotor, a breaker plate for cooperation with said rotor, an abutment plate, a compression spring interposed between said plate and abutment, a bolt and nut for adjustably limiting the action of said spring, and means operable to adjust the abutment and therewith the plate toward and away from the 75 rotor.

16. In a machine of the class described, a 80 rotor, a breaker plate for cooperation with said rotor, an abutment plate, a compression spring interposed between said plate and abutment, a bolt and nut for adjustably limiting the action of said spring, and means frangible under predetermined stress for securing the abutment in adjusted position.

In testimony whereof I have hereunto set 85 my hand.

WALTER J. ARMSTRONG.
